SELF-WRINKING MOP

Arthur Waldrop, Wellington, Kans.

Application June 8, 1948, Serial No. 31,639

1. Claim. (Cl. 15—119)

1. This invention relates to a mop and more particularly to a mop having simple and efficient means for wringing the water out of the mop cloth which is connected therewith.

The object of the invention is to provide a mop having means for holding a mop cloth and further provided with simple and efficient means for quickly and easily wringing out said mop cloth without touching the mop cloth or getting the hands in the water.

Another object of the invention is to provide a mop cloth positioned between slide means which may be moved lengthwise of the mop handle to wring the water out of the mop cloth.

Another object of the invention is to provide a mop and wringer that can be easily assembled and disassembled.

A further object of the invention is to provide a mop and wringer therefor that is so simple and rugged in design that it can be manufactured with a minimum of ease and expense.

Other objects and advantages of the invention will be apparent during the course of the following description.

In the accompanying drawings, forming a part of this application, and in which like numerals are employed to designate like parts throughout the same:

Figure 1 is a top plan view of the device, illustrating the position of the wringing mechanism when the mop is being used, according to the present invention;

Figure 2 is a top plan view of the device, illustrating the position of the wringing mechanism after the completion of the wringing step;

Figure 3 is a side elevational view of the device, with the wringing mechanism abutting the mop handle, as in Figure 1;

Figure 4 is a side elevational view of the device, the wringing mechanism being in the position shown in Figure 2;

Figure 5 is a side elevational view of the device, illustrating the separated position of the rollers, prior to movement of the rollers back to the position of Figure 1;

Figure 6 is a view showing certain constructional details of the device;

Figure 7 is a sectional view taken on the line 7—7 of Figure 6;

Figure 8 is an enlarged top plan view of the wringing mechanism, according to the present invention.

In the drawings, wherein for the purpose of illustration, is shown a preferred embodiment of the invention, the numeral 10 indicates a mop

handle. Secured to one end of the mop handle 10 is the mop cloth holder 11, Figure 2, for releasably holding the mop cloth 12. Circumposed about the mop handle 10 and connected to the mop cloth holder 11 is the coil spring 13 having an end connected to the hand hold 14. Extending between each side of the hand hold 14 and the mop cloth holder 11 is a brace 15 and 16 so that when it is desired to replace the mop cloth 12, the hand hold 14 is moved from the position shown in the drawings toward the mop cloth holder 11 to thereby release the tension maintained by the coil spring 13, thus permitting the mop cloth holder 11 to be separated for the insertion of a mop cloth 12. To lock the mop cloth 12 in the mop cloth holder 11, the hand hold 14 is swung back to the position of the drawings, wherein the hand hold 14 is arranged in superposed relation with respect to the handle 10 and maintained in such position by the braces 15 and 16.

Positioned on the mop handle 10 and arranged in spaced, parallel, relation are the clamps 17 and 18 for a purpose to be hereinafter described. The clamps 17 and 18 are fixed in position on the handle 10 by screws 9 which extend through the clamps and engage the mop handle 10.

The wringer mechanism comprises a frame Figure 2, indicated generally by the numeral 19 and embodying the pair of symmetrical arms 20 and 21. The arms 20 and 21 have one end connected to the rods 22 and 23, respectively, the rods 22 and 23 being arranged in side-by-side relation with respect to the mop handle 10 and extending through the spaced clamps 17 and 18. The ends of the rods 22 and 23 are secured to a bracket 24 which is slidably mounted on the mop handle 10 and, for sliding the bracket 24 and frame 10 along the mop handle 10, the actuating lever 25 projects from the bracket 24 and is secured thereto.

Arranged adjacent one end of the frame 19 is the transverse bar 26, said bar being disposed intermediate the arms 20 and 21. Projecting from the transverse bar 26 and secured thereto is the pair of spaced apertured ears 27 and 28. Pivotally connected to the apertured ears 27 and 28 by means of the pins 29 and 30, respectively, are the complementary links 31 and 32 which are arranged in spaced, parallel, relation with respect to each other. The ends of the links 31 and 32 are pivoted to the legs 33 and 34, respectively, of the support 35, and secured to the support 35 is the rod 36, said rod being held in side by side relation with respect to the mop handle 10 for

sliding movement therealong by means of the clamps 17 and 18, and for sliding the rod 36 and supports 35 longitudinally along the mop handle 10, the actuating lever 37 is secured to the rod 36.

Secured to each end of the transverse bar 26 is a guide link 38 and 39, the link 38 having one end pivotally connected to the arm 20 of the frame 19, by means of the pin 40, and the link 39 having one end pivotally connected to the arm 21 by means of the pin 41. Journalized in the other ends of the links 38 and 39 is the shaft 42 and rotatably mounted on the shaft 42 is the upper or first roller 43, coated with rubber or other suitable material. The first roller 43 is positioned on one side of the mop cloth 12, and positioned on the opposite side of the mop cloth 12 is the second or lower roller 44 rotatably mounted on the shaft 45, the shaft 45 being journalized in the links 46 which are arranged in spaced, parallel relation on each side of the frame 19 and formed integral with the arms 20 and 21, Figures 4, 5 and 6. The roller 43 is normally biased towards the roller 44 by means of the springs 47 and 48 arranged on opposite sides of the frame 19, the spring 47 connecting the movable link 39 to the fixed link 46, the coil spring 48 being similarly connected on the other side of the frame 19.

The operation of the mop and wringer is as follows: The mop cloth 12 is made fast to the mop cloth holder 11 of the mop handle 10 by means of the spring 13 and hand hold 14. With the rollers in the position of Figure 1, the mop cloth is immersed in a pail of water or cleaning fluid. After the mop cloth 12 has been dipped in water it may be very quickly and easily wrung out by grasping the lever 25 and moving it towards the clamp 17, thus causing the rods 22 and 23 carrying the frame 19 to be moved along the mop. As the frame 19 is moved, the upper and lower rollers 43 and 44 are moved along the mop cloth 12 to thereby squeeze the water from the cloth 13, the rollers being positioned as shown in Figure 4 at the completion of this step. After the water has been squeezed out of the mop cloth 12, the lever 25 is moved forwardly from the position shown in Figure 4 to the position shown in Figures 5 and 6, such movement causing the links 31 and 32 which are operatively connected to the transverse bar 26 to pivot the upper roller 43 out of bearing engagement with the mop cloth 12 since the arms 20 and 21 of the frame 19 will be moved forwardly, while the links 31 and 32 of the support 35 have their forward movement stopped by the lever 37 bearing against the clamp 17. With the upper roller 43 in this raised, out of contact position, the levers 25 and 37 are moved away from the clamp 17 to thereby return the frame and wringer assembly to the position of Figure 1, the lever 37 being released as soon as the mop cloth 12 is clear of the rollers, and the mop is ready to be used for mopping purposes. While the mop cloth 12 is being wrung

out, the mop will preferably be held in a generally upright position over a mop pail or like receptacle.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehend by the spirit of the invention as herein described and the scope of the appended claims.

Having described the invention, what is claimed as new is:

In a mop including a handle, a holder, and a mop cloth releasably carried by said holder, the improvement consisting of providing a wringer for squeezing water from said mop cloth, means operatively connected to said handle for actuating said wringer, said wringer comprising a frame having a pair of elongated symmetrical arms, a first pair of spaced links secured to the ends of the arms of said frame, a first rotatable roller arranged in abutting relation with respect to one side of said mop cloth, and carried by said first pair of links, a second frame positioned above said first frame and having legs of shorter length than the arms of said first mentioned frame, a second pair of links pivotally connected to the arms of said first frame, a second roller rotatably carried by said second pair of links mounted for movement toward and away from the other side of said mop cloth, resilient means embodying a coil spring connecting the respective first and second pair of links together for biasing said second roller toward said first roller, and means on said handle for moving said rollers away from each other, said means comprising said second frame, and said second pair of links being operatively connected to said second frame.

ARTHUR WALDROP.
